JAMES G. STAFFORD, OF WHITING, INDIANA, ASSIGNOR TO SINCLAIR REFINING COMPANY, OF NEW YORK, N. Y., A CORPORATION OF MAINE

ART OF REFINING HYDROCARBONS

Application filed March 30, 1928. Serial No. 265,842.

This invention relates to improvements in refining petroleum distillates. The invention is of special value and application in the treatment of light cracked petroleum distillates, for example, gasoline to be used for motor fuel, and particularly in the treatment of low boiling distillates produced by vapor phase cracking operations. The invention is also useful in the treatment of other cracked 10 distillates, such as wax distillate.

Unrefined cracked distillates contain relatively large quantities of unstable unsaturated hydrocarbons which decompose readily on standing or exposure to sunlight with the 15 formation of objectionable gum-like constituents. Low boiling distillates produced by cracking in the vapor phase in particular, contain exceptionally large quantities of these unstable unsaturated hydrocarbons. 20 Such distillates are of bad color, ranging from brilliant yellow to orange and have a disagreeable odor. In the past, treatment of these distillates to obtain satisfactory marketable products without excessive treating 25 losses has presented a serious problem and the treatment of such distillates has been accompanied by the removal, together with the more objectionable compounds, of the relatively stable constituents that are desirable 30 as components of a finished motor fuel product.

The present invention provides a novel method of operation whereby even the most highly cracked distillates from vapor phase 35 cracking operations may be readily converted at small cost with a minimum of equipment and without excessive loss of the material to be treated, into water-white distillate products which are free from disagreeable 40 odor and relatively stable even on prolonged standing or exposure to sunlight.

According to the improved process of the invention, the unrefined distillates to be treated are subjected to an elevated temperature 45 and pressure under non-oxidizing conditions in the presence of a finely divided solid adsorbent material, such as fuller's earth, and a stable hydrocarbon liquid capable of acting as a solvent for the gum-like 50

constituents or higher boiling polymers formed by the resulting reactions.

The refining process of the invention may advantageously be carried out in a continuous manner by flowing a stream of the petroleum 55 distillate to be treated in admixture with a stable hydrocarbon liquid through a body of finely divided fuller's earth or similar solid adsorbent material while maintaining the flowing stream of distillate to be treated at 60 temperatures of from about 375° F. or somewhat lower to about 500° F. or somewhat higher and a pressure at least sufficient to prevent substantial vaporization at the temperature employed, and subsequently separating the treated distillate product from the 65 stable solvent and the dissolved reaction products contained therein. Separation of the treated distillate product may be obtained, for example, by ordinary distillation, at at- 70 mospheric pressure, or, the pressure may be reduced on the mixture of treated distillate and solvent oil as discharged from the treat- 75 ing operation to effect vaporization of the lower boiling distillate by its contained heat and thereafter separating the desired test distillate by fractional condensation.

The exact temperatures and pressures to be most advantageously employed in the treatment of a given distillate will, of course, 80 vary with the character of the distillate to be treated, the kind of solvent oil used, the nature of the solid adsorbent material, the degree of refinement desired in the distillate product, the time of contact permitted and 85 the yield it is desired to obtain from a given amount of solid adsorbent medium. In gen- 90 eral, increasing either the temperature or pressure tends to increase the rate of the polymerizing reaction. The pressure may, if desired, be maintained at about the pressure required to prevent substantial vaporization at the temperature employed though higher pressures tend to promote the treating action and prolong the life of the solid adsorbent 95 material. Fuller's earth, in a finely divided state, may be satisfactorily employed as the solid adsorbent material in carrying out the process of the invention. Silica gel, acti- 100 vated carbon, bauxite and similar adsorbent

materials may be likewise used to advantage. Kerosene and gas oil have been satisfactorily employed as stable liquid solvents in carrying out the process of the invention, although other liquid hydrocarbons substantially stable in the presence of the solid adsorbent material and at the temperature and pressure employed, which are capable of acting as a solvent for the gum-like constituents and higher boiling polymers, for example, straight run gasoline, solvent naphtha, pressure still charging stock and the like, may be used to advantage as a diluent. Heavier distillates, such as gas oil, are more readily maintained in liquid state at elevated temperatures and appear to have the greater solvent action. The heavier solvents have the further advantage that they may be more readily separated by fractional distillation from the desired test distillate due to the great difference in their boiling range.

In the treatment of South Texas and Mid-Continent vapor phase cracked distillates using a blend of 80% of the unrefined cracked distillate with 20% water-white kerosene and a 60-90 mesh No. 0 Olmstead fuller's earth, temperatures of about 380° F. to 500° F. and pressures of 150 to 200 lbs. per square inch have been satisfactorily employed.

The exact relationship between the action of the objectionable unsaturated hydrocarbons contained in unrefined highly cracked distillates, the finely divided adsorbent material and the stable liquid solvent in effecting the removal of the former is not clearly understood. It may be that the solid adsorbent material acts directly, to a certain extent, on the objectionable unsaturated constituents, although in the presence of the stable liquid solvent at elevated temperatures and pressures its action appears to closely approach that of a true catalyst. In any event, the combined action of the stable liquid solvent and solid adsorbent material at elevated temperatures and pressures is such that the objectionable constituents may be converted in the liquid phase to higher boiling polymers that may be readily separated from the desired test distillate by ordinary fractionating operations.

The relationship of the action of the solid adsorbent material and the stable liquid solvent at elevated temperatures and pressures may be best illustrated by the results of the following specific examples:

A 460° F. end-point vapor phase cracked South Texas distillate having an orange color and disagreeable odor was passed through a cell containing 60-90 No. 0 Olmstead fuller's earth. The distillate was heated to a temperature of 500° F. and maintained at a pressure of 150 lbs. per square inch during the treatment. The rate of flow through the treating cell was regulated to

permit contact of the distillate under treatment with the earth for about one hour. The treatment was discontinued after one gallon of distillate per pound of earth used had been passed through the treating cell and the treated distillate redistilled to obtain a 392° F. end-point stock. The redistilled material was found to average less than 16 Saybolt color although only one gallon of material had been treated per pound of earth used. 75

In another test a mixture consisting of 80% of the same unrefined vapor phase cracked distillate and 20% water-white kerosene was passed through the treating cell under the same conditions employed in the previous test. This time the treatment was continued until more than two gallons per pound of earth used had been passed through the treating cell and was stopped only because of shortage of charging stock. The treated material was then redistilled as in the previous test. The redistillation yielded a 30+ Saybolt color motor fuel which had a sweet odor and was stable even on prolonged standing and exposure to sunlight. 80 85

In another test a mixture consisting of 80% Mid-Continent vapor phase cracked gasoline, having an initial boiling point of about 120° F. at atmospheric pressure, and 20% water-white kerosene was passed through the treating cell at a temperature of 380° F. and pressure of 200 lbs. per square inch. The test was continued until about 4 1/4 gallons of oil per pound of earth had been passed through the treating cell. The motor fuel fraction obtained on redistillation of even the last material to pass through the "reati- 90 95 100 105 110 115 120 125 130 135 140 145 150 155 160 165 170 175 180 185 190 195 200 205 in the autoclave treatment that the reactions which took place in the treating cell in the last test were accomplished with all parts of the charge in a liquid condition.

5 In still another test a mixture consisting of 80% unrefined Mid-Continent vapor phase cracked distillate and 20% water-white kerosene was passed through a treating cell containing a fresh charge of 60-90 No. 0 Olmstead earth at the same rate as that employed in the previous tests. A temperature of 450° F. and pressure of 150 lbs. per square inch were maintained on the oil during treatment and the operation continued until about 6 1/4 10 gallons of the mixture per pound of earth used had passed through the treating cell. The treated distillate was then redistilled as before. The test gasoline so obtained was found to have a 21+ Saybolt color and a 15 sweet odor, and to be substantially stable on standing and exposure to sunlight. The 20 yield of treated test gasoline based on the latter test was found to be approximately 225 barrels per ton of fuller's earth charged to 25 the treating cell.

In carrying out the process of the invention the polymerization losses will vary considerably with the character of the distillate to be treated and the degree of refinement desired in the finished product. In the treatment of a very highly cracked distillate the polymerization losses may, for example, be as high as 10% while in the treatment of cracked distillates from ordinary liquid phase cracking operations, by the process of the present invention, polymerization losses are negligible. In the treatment of very highly cracked distillates the polymerization losses will also vary somewhat during the 30 treating operation, being slightly higher during the initial stages when the solid adsorbent material is fresh. In any case, however, substantially all of the more unstable unsaturated hydrocarbons suitable as components of a motor fuel remain in the final 35 treated and redistilled product. The polymerized products may to advantage be subjected to further cracking treatment and an additional yield of the desired distillate product obtained therefrom and therefore do not represent a true loss comparable to the 40 sludge loss in the usual acid treatment.

The invention will be further described in connection with the accompanying drawings 45 which illustrate one form of apparatus adapted for carrying out the process of the invention. It will be understood that this more detailed description of the invention is intended as an exemplification of the invention and that the process of the invention is not limited thereto.

50 Referring to the drawing, the apparatus illustrated comprises a heater 1 and two treating cells 2 and 3, each of which is provided 55 with appropriate ports or removable heads

for supplying and discharging finely divided solid material and with suitable screens to prevent the escape of such solid material from the cells, a fractionating tower 4, a condenser 5 and a pump 6 provided with suitable connections for conveying distillates to be treated through the heater to the treating cells. Cells 2 and 3 are filled with a finely divided solid adsorbent, such as fuller's earth or similar adsorbent material. These cells 70 are arranged in duplicate to permit discharging and recharging of one while the oil under treatment is flowing through the other. The heater 1 may be any suitable type of heating element adapted to heat the oil uniformly to the desired temperature during its 75 passage therethrough. For example, the heating coil 1 may be heated by circulating hot products of combustion thereover from a furnace (not shown). The treating cells 2 80 and 3 and the connections between the heater and the treating cells may to advantage be lagged or mildly heated externally to prevent loss of heat by radiation during the 85 treating operation. In the apparatus illustrated the pressure on the treating cells may be regulated and the rate of flow of oil through the treating cells controlled by the 90 valves 7, 8 and 9 and the pump 6 so as to maintain any desired pressure on the oil during treatment, and so that the period of time over which the oil is in contact with the adsorbent material is sufficient to effect conversion of the unstable unsaturated hydrocarbons to higher boiling polymers which 95 may be readily separated from the desired test distillate by fractional distillation or condensation. Valved connections 10 and 11 are adapted to supply the unrefined cracked distillate and a stable liquid solvent in regulated 100 amounts from suitable sources of supply to the pump 6. Following treatment with the solid adsorbent material the treated mixture may be discharged directly to the lower end of fractionating tower 4. The pressure on 105 the mixture may be reduced at the valve 7 to effect vaporization of the lower boiling components thereof by its contained heat and the vapors so generated separated from the higher 110 boiling solvent and dissolved material in 115 the fractionating tower 4. The treated gasoline product may be taken off as vapor from the top of the fractionating tower and condensed to form the desired test gasoline product. The heavier solvent oil containing the dissolved higher boiling polymers 120 may be drawn off as a liquid from the bottom of the tower 4 and led to a suitable storage tank or subjected to further treatment. For example, the solvent oil and dissolved constituents may be charged directly while hot to a pressure still, wherein both the solvent oil and higher boiling polymers may be subjected to further cracking treatment. This method of operation is particularly advantageous 125 130

when pressure still charging stock is employed as a liquid solvent in the treating operation. The hot treated mixture in the treating cells may, if desired, be drawn off directly through the valved branch connection 12, or through the condenser 5 by means of the by-pass connection 13, the condenser acting as a cooler in the latter case to prevent flash evaporation when the pressure is reduced if the treated mixture is to be discharged to a storage tank. If the treated cracked product is to be blended with a straight run gasoline, a portion of the straight run gasoline may with advantage be used as the stable solvent liquid required in the treating operation. The treated mixture may also be drawn off through valved branch connection 12 while hot to an ordinary rerun still and redistillation of the cracked treated product carried out in conjunction with distillation of the product with which the test gasoline from the treated mixture is to be blended.

It will be apparent that in carrying out the process of the invention the oil might be passed through a series of cells charged with solid adsorbent material and as the charge in one or more of the cells became exhausted the other charges in the series might be advanced so that the oil discharged from the apparatus will always be last contacted with the freshest charge of solid adsorbent material.

It is one of the advantages of the process of the invention that its simplicity makes it well adapted to continuous operation. The control of the operation involves simply the maintenance of contact between the mixture of unrefined cracked distillate and stable liquid solvent and the solid adsorbent material at an elevated temperature and pressure for a period of time sufficient to effect conversion of the desired amount of unstable unsaturated hydrocarbons required in any particular case so that the attention of a skilled operator is, accordingly, not essential.

I claim:

1. The improvement in the refining of cracked hydrocarbon distillates comprising admixing therewith a liquid hydrocarbon having a higher boiling range than said distillate, said liquid hydrocarbon being capable of acting as a solvent for the higher boiling reaction products formed in the refining operation and substantially stable under the conditions of the refining operations, and subjecting the mixture in a liquid state to an elevated temperature lower than that at which substantial cracking will occur and simultaneously to an elevated pressure in the presence of a finely divided solid adsorbent material.

2. The improvement in the refining of cracked hydrocarbon distillates comprising admixing with said cracked distillate a liquid hydrocarbon more stable than said cracked

distillate under the conditions prevailing in the refining operation and capable of acting as a solvent for the higher boiling reaction products formed in the refining operation, and subjecting the mixture in a liquid state to a temperature lower than that at which substantial cracking will occur but in excess of about 375° F. in the presence of a finely divided solid adsorbent material.

3. The improvement in the refining of cracked hydrocarbon distillates comprising admixing a kerosene-character distillate with said cracked distillate, subjecting the mixture to a temperature lower than that at which substantial cracking will occur but in excess of about 375° F. in the presence of finely divided fuller's earth, and maintaining a superatmospheric pressure in excess of that required to prevent substantial vaporization of said distillates during the treating operation.

4. An improved method of refining cracked hydrocarbon distillates comprising admixing with said cracked distillate a liquid hydrocarbon more stable than said cracked distillate under the conditions prevailing in the refining operation and capable of acting as a solvent for the higher boiling reaction products formed during the refining operation and subjecting the mixture in a liquid state to a temperature lower than that at which substantial cracking will occur but in excess of about 375° F. in the presence of a finely divided solid adsorbent material, and subsequently separating the treated distillate from the stable liquid solvent and higher boiling reaction products dissolved therein.

5. The improvement in the refining of cracked hydrocarbon distillates comprising admixing with said cracked distillates a liquid hydrocarbon more stable than the said cracked distillates under the conditions prevailing in the refining operation and capable of acting as a solvent for the higher boiling reaction products formed during the refining operation, subjecting the mixture to a temperature of about 375° to 500° F. in the presence of a finely divided solid adsorbent material and maintaining a superatmospheric pressure on the mixture during treatment in excess of that required to prevent substantial vaporization of said distillate.

6. The improvement in the refining of cracked hydrocarbon distillates comprising admixing with said cracked distillates a hydrocarbon liquid more stable than the said cracked distillates under the conditions prevailing in the refining operation and capable of acting as a solvent for the higher boiling reaction products formed during the refining operation, subjecting the mixture in a liquid state to a temperature of about 375 to 500° F. in the presence of a finely divided solid adsorbent material, and maintaining a superatmospheric pressure of about 150-200

lbs. per square inch on the mixture during the treatment.

7. An improved method of refining low boiling cracked hydrocarbon distillates comprising admixing with said cracked distillates a liquid hydrocarbon more stable than said cracked distillates under the conditions prevailing in the refining operation and capable of acting as a solvent for the higher boiling reaction products formed during the refining operation, passing a stream of the mixture in intimate contact with a finely divided solid adsorbent material, maintaining the mixture of low boiling cracked distillates and stable liquid hydrocarbons at a temperature lower than that at which substantial cracking will occur but in excess of about 375° F. and at a pressure in excess of that required to prevent substantial vaporization at the temperature employed during contact with said finely divided solid adsorbent material, and subsequently reducing the pressure on the treated mixture to effect vaporization of the low boiling cracked distillates.

In testimony whereof, I have subscribed my name.

JAMES G. STAFFORD.
